(57) **CLAIM**

The ornamental design for a display screen or portion thereof with graphical user interface, as shown and described.

DESCRIPTION

FIG. 1 is a front view of a display screen or portion thereof with graphical user interface showing a first embodiment of the claimed design;

FIG. 2 is a front view of a display screen or portion thereof with graphical user interface showing a second embodiment of the claimed design;

FIG. 3 is a front view of a display screen or portion thereof with graphical user interface showing a third embodiment of the claimed design;

FIG. 4 is a front view of a display screen or portion thereof with graphical user interface showing a fourth embodiment of the claimed design;

FIG. 5 is a front view of a display screen or portion thereof with graphical user interface showing a fifth embodiment of the claimed design;

FIG. 6 is a front view of a display screen or portion thereof with graphical user interface showing a sixth embodiment of the claimed design;

FIG. 7 is a front view of a display screen or portion thereof with graphical user interface showing a seventh embodiment of the claimed design;

FIG. 8 is a front view of a display screen or portion thereof with graphical user interface showing a eighth embodiment of the claimed design; and,

FIG. 9 is a front view of a display screen or portion thereof with graphical user interface showing a ninth embodiment of the claimed design.

The outermost broken line in the figures shows a display screen, or a portion thereof, and forms no part of the claimed design. The other broken lines in the figures show portions of the graphical user interface that form no part of the claimed design.

1 Claim, 9 Drawing Sheets
